METHOD OF DYEING, EXTRACTING, AND
DRYING VARIOUS TEXTILES, AND THE
APPARATUS THEREFOR

Ernest A. Stienen, New York, N. Y.

Application April 27, 1937, Serial No. 139,180

3 Claims. (Cl. 8—156)

This invention relates to the method of dyeing, extracting and drying various textiles and the apparatus therefor.

One of the objects of the invention relates to the method of dyeing, extracting surplus fluids from and drying worsted, tops of wool, rayon and other textiles and the apparatus therefor.

The second object of the invention relates to the treatment of textiles without manually contacting with the same, during the dyeing, extracting surplus fluids and drying the same and the apparatus therefor, to avoid injury to said textiles and prevent blotches being formed thereon.

15 The third object of the invention relates to the dyeing of textiles and the extracting of surplus fluids therefrom with the requisite appurtenances, and the removal of the textiles to other appurtenances to dry them without the operator manually contacting with said textiles.

In the drawings, Fig. 1 represents a plan view of a dyeing, extracting and drying machine; Fig. 2 shows a section on a reduced scale of Fig. 1 on the line 2, 2; Fig. 3 indicates a left-hand view and partial section of Fig. 1 on the line 3, 3; Fig. 4 is an enlarged section of Fig. 3 on the line 4, 4; Fig. 5 represents a plan view of an additional drying machine; Fig. 6 shows a lefthand side view of Fig. 5; Fig. 7 indicates an enlarged section of Fig. 5 on the line 7, 7; Fig. 8 shows an enlarged vertical section of a pair of pots for drying and Fig. 9 is an enlarged fragmentary portion in vertical section of Fig. 7.

Referring to Figs. 1, 2, 3, 4 and 8, a foundation block is indicated at 20 with the recess 21. A tank designated in its entirety by the numeral 25 is supported upon the foundation block 20. The tank 25 comprises the front wall 26, rear wall 27, side walls 28 and the bottom wall 29. An opening 32 is indicated in the wall 29 and an annular flange 33 is fastened to the lower face of the wall 29 and which is coaxial with the opening 32.

A foundation block is shown at 36. An electric motor 37 having the armature shaft 38 is supported upon the block 36. A pump 40 is also supported upon the block 36 and is coupled to said electric motor 37 by means of the coupling 41. A four way valve 44 having the regulating handle 44a is connected to the pump 40. Outlet piping 45 with the valve 46 and the outlet nozzle 47 extends from the four way valve 44. Piping 48 extends from the four way valve 44 to the opening 32.

55 A pair of conduits 50 having the connecting

flanges 51 are positioned in the lower portion of the tank 25. Pairs of branch pipes 52 each having the annular flange 53 extend from the conduits 50. Piping 55 connects the four way valve 44 and the conduits 50. A valve 56 is indicated in the piping 55.

A plurality of receptacles each designated in its entirety by the numeral 60, are shown in the tank 25. Each of the receptacles 60 comprises the vertical cylindrical wall 61 and the bottom 10 wall 62 having the axial opening 63. The upper end of the wall 61 has integral therewith the turned overend 64. To the wall 62 is fastened the reinforcing disc 65 having the axial opening 66.

Upon the bottom wall 62 is positioned the sleeve designated in its entirety by the numeral 70. At the lower end of the sleeve 70 is shown the annular flange 71 and openings 72 extend through the wall of the sleeve 70.

Upon the sleeve 70 is supported the spherical hood 75 having the perforations 76. The circumferential edge of the hood 75 bears on the curved jointure of the walls 61 and 62. A short threaded plug 78 may extend through the hood 25 75 and in threaded engagement with the upper end of the sleeve 70, see Fig. 8, or a longer plug 79, see Fig. 4 may be substituted for the plug 78.

At the upper end of the vertical wall 61 are secured in this instance three clamping hooks 80. 30

A detachable cover 84 is provided for each receptacle 60. Each cover 84 is shown with the bent over circumferential edge 85 and has extending therethrough a plurality of openings 86. A pair of handles 87 extend up from each cover 84 and clamping hooks 88 extend from each cover which are adapted to lock with the clamping hooks 80.

To position the covers 84 in place they are inserted into the top end of the receptacles 60, 40 with the clamping hooks 88 spaced from the clamping hooks 80. The cover 84 is then turned to engage the clamping hooks 88 with the clamping hooks 80 when the cover will be located in operative position. From the valve 56 extends 45 the piping 92.

A cylindrical tank is indicated at 95 with the bottom 96 and the detachable cover 97. A baffle plate 98 extends from the cover 97. The piping 92 leads to the upper end of the tank 95. 50 A drain pipe 99 with the valve 100 leads from the lower end of the tank 95.

A foundation block is indicated at 104 upon which is supported the electric motor 105 having the armature shaft 106. A pump designated in 55

its entirety by the numeral 110 is connected to the armature shaft 106.

Conduits 111 and 112 extend from the pump 110. Piping 115 having the valves 116 and 117 has one end 118 connected to the tank 95 and is also connected to the inlet conduit 111. Piping 119 and 120 leads from the piping 115. The piping 120 is connected to the conduit 112. Valves 121 and 122 are connected to the piping 120. A gutter is indicated at 130.

The apparatus indicated in Figs. 1, 2, 3 and 4 which can be used to dye textiles, extract surplus fluids from them and dry them is operated as follows:

15 The covers 84 are detached from the receptacles 60, and the textiles T to be treated are inserted in said receptacles and the covers replaced in position. The valves 46 and 56 are closed and the dye liquor is poured into the tank 25. The electric motor 37 is energized, by means not shown, and the dye liquor, in one position of the four way valve 44 draws the dye liquor from the tank 25 in the direction of the arrow A, Fig. 1. The dye liquor flows through the pump 40 and is discharged from the four way valve 44 to the conduits 50 and flows in the latter in the direction of the arrows B. The dye liquor flows from the conduits 50 into the branch pipes 52 and from the latter enters the receptacle 60 in the direction of the arrows C, see Fig. 4, when the short plugs 79 are used. The long plugs 78 are used to shut off any of the receptacles 60. The dye liquor is forced through the textiles T in the receptacles 60 and escapes through the openings 86 of the covers 84 and flows into the tank 25. From the tank 25 the dye liquor flows through the opening 32 to again enter the four way valve 44 to be again circulated as described.

After a predetermined number of circulations 40 of the dye liquor its direction may be reversed by means of the four way valve 44 in which case the dye liquor enters the receptacles 60 through the openings 86 of the covers 84 and flows into the four way valve 44, through the opening 32. After the textiles have been dyed the dye liquor may be drained from the tank 25 through the four way valve 44 and the outlet nozzle 47, the valve 46 having been opened. The used dye liquor then escapes in the gutter 130.

50 The surplus fluids in the textiles T in the receptacles 60 are next extracted as follows:

The valves 56, 116 and 122 are opened and the valves 117 and 121 are closed. The electric motor 105 is energized and the pump 110 produces a suction effect and the surplus liquor is drawn into the tank 95. The vapors in the liquor are drawn into the pump 110 and from the latter they escape through the valve 122 and the piping 120. The liquor may flow from the tank 60 by opening the valve 100. The textiles may then be removed from the receptacles 60, to be dried by the appurtenances shown in Figs. 5 to 9, which steps will be explained, or the said textiles 65 may remain in the said receptacles 60 and be dried as follows: The electric motor 105 is energized. The valves 117 and 121 are opened and the valves 116 and 122 are closed. Air which may be heated enters the pump 110 through the piping 115 and conduit 111. The said air flows 70 through the conduit 112, the valve 121, through the tank 95, through the valve 56 which is open and then through the conduits 50 up through the receptacles 60 and from the latter escapes 75 through the openings 86.

Referring to Figs. 5, 6, 7, 8 and 9, the additional drying apparatus comprises the following:

Foundation block 140 having supported thereon the pair of conduits 143 each closed at one end by the cap 144. The said conduits 143 at 5 their other ends are connected by the piping 145. A foundation block 148 supports a pump 149 and an electric motor 150 to drive said pump 149. A heater 151 is interposed between the pump 149 and the piping 145. From the conduits 143 extend 10 pairs of branch pipes 154. From each branch pipe 154 upwardly extends the piping 156 having the valves 156a. The piping 156 is shown with the upper threaded ends 157. To each threaded end 157 is detachably screwed the conical shaped support 160. Each of the supports 160 has detachably positioned therein the conical foot 162 having the conical shaped wall 163. Integral with the wall 163 is shown the conical support 165 with the straight tubular supporting 20 end 166 having the threads 167 on its interior face.

Receptacles are indicated in their entireties by the numeral 170. Each of the receptacles 170, see Figs. 7 and 8 comprises the cylindrical wall 171 25 open at its top end and the bottom wall 172. A reinforcing band 173 is secured to the upper end of the wall 171 and a plurality of locking lugs 174 extend from the band 173. A row of openings 176 extend through the upper portion of the wall 170 30 and pairs of openings 178 extend through the wall 171 above the openings 176. A detachable cover 180 is provided for each receptacle 170. Each of the latter covers has extending therethrough the openings 181 and has also extending 35 therefrom the handles 182. Clamping hooks 185 extend from the cover 180 which are adapted to lock with the locking lugs 174. Supporting rods 188 may be detachably supported in the openings 178. At the lower inner end of each 40 receptacle 170 is secured the spherical hood 190 having the perforations 191.

An annular reinforcing plate 195 is secured to the bottom wall 172 of each receptacle 170. A threaded nipple 196 connects the bottom wall 45 172 of each receptacle and the supporting end 166 of the support 165.

Any of the receptacles 170 may be shut off from the apparatus by the valve 156a.

In case the textiles in the receptacles 60 are 50 to be dried in the receptacles 170, the covers 84 of the receptacles 60 are removed and the receptacles 170 are placed upon the receptacles 60 as indicated in Fig. 8, with the reinforcing bands 173 bearing on the turned over ends 64 of 55 said receptacles 60 and the locking lugs 174 are locked with the clamping hooks 80. The valves 116 and 122 are closed and the valves 117 and 121 are opened. The electric motor 105 is energized and a stream of air enters the pump 110 60 through the piping 115 and conduit 111, and is discharged from the pump 110 through the conduit 112. The air then flows through the valve 121 into the tank 95 and from the latter is directed to the conduits 50. From the conduits 65 50 the air enters the receptacles 60 and blows on the textiles T from said receptacles 60 into the receptacles 170 as indicated in Fig. 8. When the receptacles 170 are filled with the textiles, the supporting rods 188 are pushed through the 70 openings 178, to hold said textiles in place in said receptacles 170. The receptacles 170 are then removed from the receptacles 60 and turned with their open ends up. The rods 188 are removed and the receptacles 170 with their covers 75

180 in place are positioned with their feet 162 supported in the supports 160, see Figs. 7 and 9.

The electric motor 150 is energized and air is drawn into the heater 151 from which it is discharged into the piping 145. From the latter the heated air enters the conduits 143. The air next flows through the branch pipes 154 and then into the receptacles 170 and the textiles in said receptacles are dried. The air finally 10 escapes through the openings 181 and the openings in the upper end of each receptacle 170.

Various modifications may be made in the invention and the present exemplification is to be taken as illustrative and not limitative thereof.

15 Having described my invention, I claim:

1. The method of treating a textile, devoid of manually contacting with the same, consisting in locating the textile in a receptacle, dyeing said textile while in said receptacle, extracting surplus fluids from said textile while in said receptacle, blowing said textile from said receptacle into a second receptacle with a stream of air and finally drying the textile with a stream of air.

25 2. The method of simultaneously treating a

group of textiles, devoid of manually contacting with the same, consisting in locating the textiles in a group of dye receptacles simultaneously dyeing said group of textiles while in said receptacles, simultaneously extracting surplus fluids from said textiles while in said receptacles, simultaneously blowing said textiles from said receptacles with streams of air into a second group of receptacles, blowing streams of air through the textiles and removing said textiles from the 10 second group of receptacles.

3. In an apparatus of the character described the combination of a lower receptacle for a textile, an upper receptacle positioned with its open end down, means to detachably lock the upper receptacle above and to the lower receptacle, means to blow streams of air into and through the lower receptacle to blow the textile therein into the upper receptacle, a conduit, piping extending from said conduit, means to detachably connect 20 the upper receptacle to said piping and means to force air through the textiles in the said upper receptacle.

ERNEST A. STIENEN. 25
